DESIGN FOR A WALKING SUPPORT FOR INVALIDS

Karl R. Vaught, Indianapolis, Ind.

Application October 15, 1937, Serial No. 72,205

Term of patent 7 years

To all whom it may concern:

Be it known that I, Karl R. Vaught, a citizen of the United States, residing at Indianapolis, in the county of Marion and State of Indiana, have invented a new, original, and ornamental Design for a Walking Support for Invalids, of which the following is a specification, reference being had to the accompanying drawing, forming a part thereof.

The figure is a perspective view of a walking support for invalids, showing my new design.

I claim:

The ornamental design for a walking support for invalids, as shown.

KARL R. VAUGHT.
